(57) **CLAIM**

The ornamental design for a front face of a vehicle wheel, as shown and described.

DESCRIPTION

FIG. 1 is a perspective view of the front face of the wheel according to the present invention; and,

FIG. 2 is a front elevational view thereof.

The broken lines depict portions of the front face of a vehicle wheel that form no part of the claimed design.

1 Claim, 2 Drawing Sheets

FIG. 1

FIG. 2
